(57) **CLAIM**

The ornamental design for a spray container, as shown and described.

DESCRIPTION

FIG. 1 is a perspective view of the spray container embodying our new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom view thereof.

The container is shown and described. The body of the container has a semicircular shape at the front. The neck portion of the container has several curved lines.
